UNITED STATES PATENT OFFICE.

GABRIEL WINTER, DECEASED, BY OTTO WOLFRUM, ADMINISTRATOR, OF VIENNA, AUSTRIA-HUNGARY, AND FRIEDRICH EICHBERG, OF BERLIN, GERMANY; SAID WINTER AND SAID EICHBERG ASSIGNEES TO GENERAL ELECTRIC COMPANY, A CORPORATION OF NEW YORK.

DYNAMO-ELECTRIC MACHINE.

1,073,311.

Specification of Letters Patent. Patented Sept. 16, 1913.

Original application filed June 11, 1902, Serial No. 111,180. Divided and application filed August 3, 1906, Serial No. 329,022. Divided and this application filed January 9, 1912. Serial No. 670,162.

To all whom it may concern:

Be it known that we, OTTO WOLFRUM, residing at Vienna, Austria-Hungary, administrator of the estate of GABRIEL WINTER, deceased; whose certificate of authority is recorded at page 438 of Liber S 90 of Transfers of Patents, and FRIEDRICH EICHBERG, a subject of the Emperor of Austria-Hungary, residing at Berlin, in the Empire of Germany, severally declare that the late GABRIEL WINTER and the said FRIEDRICH EICHBERG have invented certain new and useful Improvements in Dynamo-Electric Machines, of which the following is a specification.

This application is a division of a former application filed by the said Gabriel Winter and Friedrich Eichberg, on August 3rd, 1906, Ser. No. 329022, (Patent No. 1,016,865 of February 6, 1912) which is in turn a division of an earlier application filed by them on June 11, 1902, Ser. No. 111,180, (Patent No. 1,016,866, of Feb. 6, 1912.) In those former applications there are described alternating current machines of the commutator type in which the two members of the motor are provided with primary and secondary windings, respectively, arranged to produce a single magnetization along a fixed line constituting the working axis, and there is added to the primary and secondary windings a third winding so arranged that the current in it produces a magnetic field having an axis which makes an angle with and is preferably at right angles to the said working axis. As described in the said former application, Ser. No. 329,022, this third, or exciting winding is placed upon the rotor, either as an independent winding or in combination with the secondary winding, and current is supplied to it through a second system of brushes displaced 90 electrical degrees from the other brushes. More specifically there is described in that application and illustrated in Figure 5 thereof, a motor of this type in which the exciting winding is connected in series with the rotor working winding, so that the current is in phase with the working current. The present application relates specifically to this last modification.

The invention will best be understood by reference to the accompanying diagram-

matic drawing, which is identical with Fig. 5, of the former application, Ser. No. 329,022 55 and with Fig. 10 of the former application, Ser. No. 111,180.

Let the primary and secondary winding systems (hereinafter called P and S) of an alternating current transformer be arranged in the manner illustrated in this diagrammatic drawing, *i. e.*, as separate bipolar ring windings disposed in such a way that S can move independently of P, while the magnetic poles of S are maintained on the line *x x* (constituting the working axis), which can be easily attained by providing the winding S with a segmental commutator provided with brushes situated on the line *x x*. If now there be added to the windings P and S a winding M so arranged that the current in it produces a magnetic field having the axis *y y* substantially 90 electrical degrees displaced from the axis of the field of the windings P and S, and if the current supplied to the winding M corresponds as nearly as possible in phase to the currents in P and S; then a torque is produced which is proportional to the field of winding M, to the ampere turns of the 80 rotor S and to the cosine of the angle of displacement of phase between these last magnitudes. Upon rotation of the rotor in the field having an axis *y y*, *i. e.*, the field of winding M, there is generated a counter-electromotive force which has its greatest effective value on the line *x x* and is in phase with the magnetic field having the axis *y y*, since it is generated by rotation in that field. If the phase angle between 85 the electromotive force connected to S (this electromotive force being hereinafter referred to as E^2) and the magnetic field of M is very small, and the influence of the magnetic leakage and ohmic loss is disregarded, then the counter-electromotive force due to the rotation, which is in phase with the magnetic field of M, is consequently nearly in phase with, *i. e.*, in the same or opposite direction to, the electromotive force connected to the rotor, and also with the electromotive force generated in the rotor by the primary field on the axis *x x*, since this latter electromotive force is substantially in phase with the electromotive force E^2 100 impressed on the secondary. 105

In the arrangement shown in the drawing the winding P is placed on the motor and is subjected to the full potential E' . The winding S is placed on the rotor and is connected at intervals to a many-part commutator in which the brushes $B' B^2$ bear on the line $x x$; and the winding M is also placed on the rotor and is provided with a commutator distinct from the commutator to which the winding S is connected, this commutator being provided with the brushes $B^3 B^4$ arranged on the line $y y$ and connected in series with the brushes of the working rotor winding S . In this way the field is excited by current coming from the brushes, and a field winding system of few turns can be used in order to permit the use of a low voltage at the commutator, instead of a system of many turns such as would be suitable when the field M is excited from an external source of comparatively high voltage. With this arrangement, furthermore, the field M must obviously be always in phase with the rotor current.

In the arrangement described it is evident that the field produced on the line $x x$ by the currents in windings P and S , which is the field that produces the counter-electromotive force in winding P and the secondary induced electromotive force in winding S , is 90° out of phase with the voltage impressed on winding P . The field produced on the line $y y$, however, is approximately in phase with the currents in windings P and S , since winding M is connected in series with winding S . The two fields tend to produce a rotary field which is more or less uniform, according as the two component fields vary in relative strength and the phase of the currents in windings P and S varies relatively to the voltage impressed on winding P ; and this rotary field is produced without the necessity of providing external sources of voltages of different phases for the currents supplied to the winding P and to the winding M respectively.

Machines constructed in accordance with the invention can be used as generators, because upon excitation through the magnetic field of any given strength an electromotive force must in all cases arise at the rotating armature, and this electromotive force, quite independently of the number of revolutions of the rotor, is equal in phase and periodicity with the magnetic field.

The figure illustrates a bipolar arrangement merely by way of example. For an apparatus having a greater number of poles the magnetic axes $x x$ and $y y$ are, generally stated, inclined to one another at an angle of 90° divided by half the number of poles, or 90 electrical degrees.

The windings on the stator are herein

shown as ring windings, but it must be understood that all known and suitable open or closed windings can be used. The windings on the rotor are shown also as ring windings but all suitable closed windings such as are used for continuous currents and with segmental commutators can be used. 70

What we claim is:

1. An alternating current machine of the commutator type having a rotor, a stator entirely surrounding the rotor and separated therefrom by a substantially uniform air gap, brushes and connections therefor coöperating with the rotor windings to form a path for the working currents along approximately the line of the primary field, and connections for supplying to the rotor 80 an exciting current at an angle to the line of the primary field and in series with and consequently in phase with the working currents.

2. An alternating current machine of the 85 commutator type having a rotor, a stator surrounding the rotor and separated therefrom by a substantially uniform air gap, brushes and connections therefor coöperating with the rotor windings to form a 90 path for the working currents along approximately the line of the primary field, separate brushes at an angle to the first, and connections for feeding to the separate brushes an exciting current in series with 95 and consequently in phase with the working currents.

3. An alternating current machine of the commutator type having a rotor, a stator entirely surrounding the rotor and separated 100 therefrom by a substantially uniform air gap, brushes and connections therefor coöperating with the rotor windings to form a path for the working currents along approximately the line of the primary field, 105 separate brushes displaced substantially ninety electrical degrees from the first set of brushes, and connections for feeding to the separate brushes an exciting current in series with and consequently in phase with 110 the working currents.

In testimony whereof we affix our signatures in the presence of two witnesses.
